United States Patent Office

Des. 197,917
Patented Apr. 7, 1964

197,917

TRANSMISSION

Ernest R. Casale, Whittier, Calif.
(939 Goodrich Blvd., Los Angeles, Calif.)

Filed Mar. 23, 1962, Ser. No. 69,402

Term of patent 3½ years

(Cl. D55—1)

FIG. 1 is a perspective view showing the front, top and one side of a transmission embodying my new design;

FIG. 2 is a perspective of the front and the other side thereof; and

FIG. 3 is a perspective view of the rear thereof;

FIG. 4 is a reduced bottom plan view thereof;

FIG. 5 is a sectional view taken on line 5—5 of FIG. 1.
I claim:

The ornamental design for a transmission, as shown,
